UNITED STATES PATENT OFFICE.

ROY WALTER JOHNSON, OF CHICAGO, ILLINOIS, ASSIGNEE TO LESTER-JOHNSON CO., OF MINNEAPOLIS, MINNESOTA, A CORPORATION OF MINNESOTA.

HEADLIGHT REFLECTOR.

Application filed February 9, 1924. Serial No. 691,716.

My invention relates to a reflector for the above mentioned purposes, which is based upon the principle of reflection from a surface having as its elements parabolic curves 5 of the same formula and having the same focus, but having a constantly changing axis in a horizontal plane.

The object of my invention is to improve the apparatus shown and described in the 10 patent to Lester No. 1,417,926, issued May 30th, 1922.

I do not limit myself to the parabola, since this invention may be applied to any other desired conic section curve or modification of such curve.

The invention consists generally in the apparatus as described and particularly pointed out in the claim.

In the accompanying drawings forming 20 part of this specification;

Figures 1 and 2 are diagrammatic views illustrating the method of generating the reflector surface;

Figure 3 is a plan view of the horizontal 25 plane C showing the method of rotation about point F;

Figure 4 shows the pattern of light from a circular parabolic reflector (a) with a theoretical point source of light at the focus 30 (b) with an electric headlight bulb filament at the focus and (c) from a reflector made as described herein with same bulb filament at focal point;

Figure 5 shows pattern from new reflector 35 as in 4 (c) except that the greatest angular spread or movement of axis occurs at a point below the horizontal meridian;

Figure 6 shows the shape of the mouth of a reflector wherein the axis is turned both 40 horizontally and vertically, tracing the path HVH' in the plane of the reflector mouth;

Figure 7 shows pattern of light from reflector as described (Figure 6) with both vertical tilt and horizontal spread to the 45 axis.

Figure 8 is a horizontal sectional view on the line 8-8 of Figure 9 showing a practical device embodying the invention. Figure 9 is a view in front elevation of the reflector.

In Figure 1, planes A, B and C are 50 mutually perpendicular to each other, planes B and C intersecting in the horizontal line XY, and A and B in a line through XY and perpendicular to it, plane C being 55 horizontal.

In carrying out my invention the reflecting surface is developed as follows:

Construct a parabola P of the desired focal length or formula in horizontal plane C, its axis being the line XY and its arms 60 ending in plane A. Now if this parabola is revolved about its axis XY, a paraboloid of revolution is formed, having its circular mouth T in plane A, and its axis in line XY. Let the focus of the parabola and of the 65 resulting paraboloid be point F in the axis XY.

Now revolve the planes B and C upon point F as a pivot in such a way that they remain perpendicular to each other and 70 plane C remains perpendicular to plane A. In other words revolve planes B and C in plane C itself using point F as a pivot and retaining B and C perpendicular to each other,—until the line of intersection of B 75 and C makes any desired angle with its original position XY. Let this new position of the intersection of B and C be denoted by MN in Figure 2. Parabola P now assumes the position P' in the plan view of 80 plane C (Figure 3), and the extremities of its arms are made to lie in plane A by extending or cutting off as required.

The single arm of P' which lies outside the original position of said arm in position 85 P is now rotated about its axis, the axis at the same time being turned about F as a center, and remaining in plane C, the two movements to be simultaneous and in such a ratio that when P' lies in the vertical 90 plane the axis MN coincides with its original position XY, and that when said arm of P' assumes corresponding positions making equal angles on each side of the vertical plane, the angles made by MN and XY are 95 equal. These conditions produce a reflecting surface which is symmetrical about the vertical plane B, and in which the angular movement of the axis MN on either side of its original position XY reaches a maximum 100 at any desired pair of elements symmetrical with regard to vertical plane B, said angular movement being zero when the single arm of parabola P' lies in the vertical plane; that is after it has rotated 90° and 270°.

This combination of movements produces a reflecting surface composed entirely of parabolic elements having the same formula or focal length and focus point, but with 105 constantly changing angular movement of 110

their axes about the focus point as a pivot, all of the axes lying in a horizontal plane.

The effect of such a reflector with the source of light at the focus will be to spread 5 all light rays in a desired ratio, starting with no spread at the vertical element and increasing by any desired ratio to certain symmetrical points on each side of the vertical element, then decreasing to become zero 10 as the vertical element is reached again 180° from the first position.

Figure 4 shows the pattern of light from 15 a circular parabolic reflector and the change produced by a reflector made as described above, the maximum angular movement of the axes occurring when the single arm P' (the generatrix) lies in the horizontal plane.

Figure 5 shows the pattern when maximum movement of the axes is reached with 20 P' 100° from its upper vertical position instead of 90° as in Figure 4.

This invention comprehends the use of a suitable fixed curve having a focus and the desired characteristics for the projection of 25 light from a single centrally located source of light within the reflector such, for example, as a standard automobile headlight bulb. The preferred or specific form of this invention is that heretofore described where- 30 in a parabola of suitable focal length is used to generate the desired surface. It is clear that the characteristics of the reflector disclosed above may be varied as to the amount of horizontal angular movement of the axis, 35 and as to the symmetrical positions of the generating curve P', at which the angular movement of said axis reaches a maximum during the axial rotation of the curve. There are, of course, an infinite number of 40 possible pairs of symmetrical points between the upper and lower arms of the vertical meridian, where such maximum angular movement of the axis may arbitrarily be placed. These points are determined by 45 actual construction of dies, using the desired ratio for angular axial movement and rotation angle of the generating curve.

Reference is now made to Letters Patent 50 of the United States, No. 1,417,926, granted to Charles A. Lester, this invention being designed as an improvement to said patent.

Suppose that in addition to the turning of the axis (MN) about the focus point F as a pivot, in the vertical plane as described in 55 the Lester patent, I now add a horizontal component of motion in a desired ratio and amount as described in the foregoing specifications, using only a single arm of the parabola P' revolved through one complete 60 revolution to produce my desired reflecting surface.

For example a reflector is desired which tilts or drops the rays from the vertical elements of its surface by 2 degrees (the uppermost rising rays) and decreases this 65 angle to zero at the horizontal elements. See Figure 6. In addition it is desired to spread the rays horizontally starting with zero at the vertical elements (where the tilt is a maximum) and increasing by any 70 desired ratio to a maximum angular horizontal movement of the axis MN of 3 degrees at the horizontal elements. If the movement of the point of the axis MN lying in plane A (the mouth of the paraboloid) be 75 traced as in Figure 6, its path will be the broken line HVH'. The contact point of MN with plane A tracing this path twice as follows:

With the generatrix P' at the upper vertical position (0°) the axis is at point V, as P' moves in a clockwise direction to 90° the axis follows along line HV to H. As P' moves to 180° the axis retraces line VH to V, and as P' moves to 270° the axis follows 85 line HV' to H', retracing back to V during the rotation of P' through the fourth quadrant to 0° again.

This motion accords with the Lester patent in that the axis moves away from and 90 back toward its original position in successive quadrants of the revolution of the parabola. The horizontal component of motion of the axis does not need to reach a maximum at the horizontal element however, but 95 may occur as in Figure 5 with its maximum above or below the horizontal element as the parabola P' is rotated.

I claim as my invention:

A reflector having a continuously curved 100 reflecting surface non-circular in transverse section, all the elements of said surface being the same fixed curve of suitable character for the projection of light from a single interior central focus point, but adjacent elements having continually changing axes of 105 rotation which pass through said focus point, the intersections of said axes with a plane which is perpendicular to the vertical and horizontal meridian planes of the reflector forming a locus with its ends in the horizontal meridian plane on each side of the vertical meridian plane, and with an intermediate point of said locus lying in said vertical meridian plane and below said horizontal meridian plane.

In witness whereof, I have hereunto set my hand this 31st day of January, 1924.

ROY WALTER JOHNSON.
